[57] CLAIM

The ornamental design for a panic operator for exit doors, as shown.

DESCRIPTION

FIG. 1 is a front perspective view showing our new design for a panic operator for exit doors, and which has a planar non-ornamented rear face (not shown); FIG. 2 is a front elevational view thereof;

FIG. 3 is a bottom plan view thereof;

FIG. 4 is an elevational view of the left end as seen in FIG. 2;

FIG. 5 is an elevational view of the right end as seen in FIG. 2; and

FIG. 6 is a transverse sectional view, taken substantially on line 6—6 of FIG. 1.

FIG. 1.

FIG. 2.

FIG. 3.

FIG. 4.

FIG. 5.

FIG. 6.
